HAROLD G. HALL, OF ONEONTA, NEW YORK

TELEPHONE SIGNALING

Application filed January 7, 1930. Serial No. 419,025.

This invention relates to visual telephone signaling apparatus and has for its object the provision of means for indicating to the eye a telephone call.

In large offices and business establishments where there are many telephone instruments in the same room or where there is a great deal of noise it is often difficult to tell whether a telephone has rung or to tell which of several phones has rung. By the device of the present invention, this confusion is eliminated.

The device of the present invention includes with a housing an electromagnet and condenser which are connected into the bell circuit of the telephone. When the central operator of the telephone system energizes the bell circuit to signal a call, the current passes through the circuit and energizes the core of the electromagnet. An armature is thus attracted to the core and releases a catch which holds a shutter within the housing. The shutter which forms the visual signal then assumes a signaling position by rising through the top of the housing.

The invention will be clearly understood from the drawings to which reference is now made.

Fig. I represents diagrammatically the device with its circuits, the shutter being shown in signaling position.

Fig. II represents diagrammatically the device when the shutter is not signaling.

Fig. III represents the resetting apparatus by which the shutter is moved from signaling to non-signaling position.

Referring now to Fig. I, a cord of an ordinary telephone desk stand is indicated diagrammatically. The cord is represented as having three strands differently colored, 1 being the green strand, 2 the red strand and 3 the yellow strand. Strands 1 and 2 are in the bell circuit as shown. Wires 4 and 5 connect respectively with strand 1 at 6 and with strand 3 at 7. The housing, 8, of the signal device of the present invention is mounted preferably on top of the telephone stand as shown and wires 4 and 5 enter the housing 8.

The connections of the wires 4 and 5 within

the housing, 8, are indicated diagrammatically in Fig. III. As there shown, the wire 5 connects with a condenser, 9, and wire, 4, with an electromagnet, 10. The condenser, 9, and the electromagnet, 10, are also connected by the wire, 11. An armature, 12, bears a claw or catch which may be as shown at 13 or in another position adapted to engage with the shutter, 14, to hold it out of signaling position as shown in Fig. II or to release it so that it may assume signaling position above the housing, 8, as shown in Figs. I and III. The shutter, 14, is pivoted as at 15 and may be counterweighted at 16, the counterweight, 16, causing the shutter, 14, to rise into signaling position through a slot in the top of the housing when the catch, 13, due to movement of the armature, 12, releases the pin, 17, on the shutter 14.

The shutter, 14, may be reset into nonsignaling position either by hand or when the device is located as shown in the drawings by a special means which comprises a reset rod, 18, mounted on the receiver hook, 19, and bearing against the shutter, 14.

The operation of the device is as follows.

When the central office signals a call the electromagnet, 10, is energized from the bell circuit through the wires 4 and 5. The armature, 12, with its claw, 13, is thus drawn towards the electromagnet and the shutter, 14, is released. The counterweight, 16, lifts the shutter through a slot in the top of the housing, 8, and the signal is displayed. The person called then removes the receiver from the hook, 19. The hook then rises carrying with it the reset rod, 18, which bears against the shutter, 14, and moves it about its pivot, 15, thus resetting it in non-signaling position where the claw, 13, engages the pin, 17, and holds the shutter in this position until the armature is once more moved.

It is, of course, possible to reset the shutter by simply pushing it into the housing by hand. It is also possible so to position and balance the shutter about its pivot that it will move into signaling position of its own weight as soon as released by the armature. Other arrangements of the parts may also be made without departing from the spirit

of the invention. The signaling means, however, comprises essentially a shutter adapted and arranged to assume a signaling position as soon as it is released by the armature of an electromagnet which is energized from the bell circuit of a telephone set. It is also obvious that the shutter movement may be actuated on release by means other than that shown, as, for example, by a spring.

- 10 The device is easy to install on sets at present in use and may be built into a desk instrument during manufacture. It lends itself easily to connection with a metering device showing the number of calls and when a call 15 is made the signal remains displayed until it is reset in the described manner.

What I claim is:—

1. In combination, a telephone set and visual signal means in connection therewith, the 20 telephone set comprising the usual transmitter, receiver, receiver-supporting hook, and bell or buzzer circuit controlled by the position of said hook; and the visual signal means comprising a visual signal element movable 25 into signalling and non-signalling position; a latch releasably securing the signal element in its non-signalling position; an electromagnet in circuit with the bell circuit of the telephone set for releasing said latch; means 30 for actuating the signal element, when released, into its signalling position; and means actuated by the hook upon the removal of the receiver which returns the signal element to its non-signalling position.
2. In combination, a telephone set and visual signal means in connection therewith, the 35 telephone set comprising the usual transmitter, receiver, receiver-supporting hook, and bell or buzzer circuit controlled by the position of said hook; and the visual signal means comprising a visual signal element adapted 40 to be put into and out of operation; means for putting the signal element into operation, said means including an electro-magnet in 45 circuit with the bell circuit of the telephone; and means actuated by the hook of the telephone set upon the removal of the receiver which puts the signal element out of operation.
- 50 3. In combination, a telephone set and visual signal means in connection therewith, the telephone set comprising the usual transmitter, receiver, receiver-supporting hook, and bell or buzzer circuit controlled by the 55 position of said hook; and the visual signal means comprising a visual signal element movable into signalling and non-signalling position, said signal element seeking when 60 released its signalling position; a latch releasably securing the signal element in its non-signalling position; an electro-magnet in circuit with the bell circuit of the telephone set for releasing said latch; and means actuated by the hook on the removal of the re-

ceiver which returns the signal element to its non-signalling position.

In testimony whereof, I have signed my name to this specification this 12th day of December, 1929.

HAROLD G. HALL.
